UNITED STATES PATENT OFFICE

2,460,545

SPRAY GUN

Warren M. Spreng, Ashland, Ohio, assignor to
The F. E. Myers & Bro. Company, Ashland,
Ohio, a corporation of Ohio

Original application June 15, 1940, Serial No.
345,519. Divided and this application August 7,
1942, Serial No. 453,973

3 Claims. (Cl. 299—112)

1

The present invention relates to spray guns for distributing solutions over surfaces, and particularly for applying insecticides to plants, bushes and trees.

This application is a division of my application Ser. No. 345,519 filed June 15, 1940 and entitled "Spray gun."

The usual form of spray gun is constituted of a barrel of a varying length, depending upon the use to which the gun is put, the barrel terminating at one end in a nozzle cap and at the other end in some form of a fluid shut-off. There is only one grip provided and that appears at the shut-off end, but there is no provision for adjusting the amount of shut-off to accommodate wear. Neither is there any provision for adjusting the maximum opening of the valve at the shut-off end, or the tightness with which the valve is clamped on its seat.

The entire weight of the long barrel, assuming that trees are being sprayed and call for a considerable length of barrel, is carried solely by the grip at the shut-off and in case spray fluids of considerable pressure and velocity are being handled by the gun, the user of the device finds the spraying work exhaustive.

Again, in case it is desired to change the size of the spray in guns of the unimproved type, it is usually necessary to remove the nozzle for the purpose of replacing the apertured disc in the nozzle by a disc having a different sized opening and the work of making this change can be accomplished only while the spray gun is not in use.

In the parent application of which the present case is a division there is disclosed an improved spray gun in which two grips are employed, one of the grips being positioned at the end of the barrel and constituting an improved trigger structure and the other of the grips is positioned intermediate the ends of the barrel where it can be readily held by the hand of the user. There is provided a simple and sturdy mechanism controlled by the last mentioned handle for regulating the character of the supply ejected by the nozzle and the barrel. Thus, the supply may be controlled while the gun is in continuous use and the same device that regulates the spray also serves as a second grip for supporting the barrel.

The invention covered by this divisional application is directed more especially to the spray end of the gun and mechanism by which the intermediately positioned grip handle can control the character of the spray.

Other objects and features will be apparent as

2

the following specification is perused in connection with the accompanying drawings, in which:

Figure 1 represents a longitudinal cross-section of the complete gun.

Figure 2 is a fragmentary longitudinal section of the nozzle in the barrel, also showing the intermediate grip handle and the mechanism for controlling the size of the whirl chamber at the nozzle. This figure shows a nozzle in which the whirl chamber is of minimum size.

Figure 3 is a view similar to Figure 2 but illustrating the nozzle as having been moved to a position to give the maximum size of opening.

Figure 4 is a plan view taken along line 4—4 and looking in the direction of the arrows shown in Figure 2.

Figure 5 is a sectional view taken along line 5—5 in Figure 2.

Figure 6 is a similar view taken along line 6—6 in Figure 3.

Referring more particularly to Figure 1, the improved spray gun is constituted essentially of four main parts, namely, the barrel which is generally designated by the reference character 1, the nozzle indicated 2 and positioned at one end of the barrel, the trigger shut-off 3 at the other end of the barrel, and the spray control mechanism 4 positioned intermediate the ends of the barrel.

The barrel 1 is made up of as many lengths of piping as may be desired and, as indicated, there are two lengths formed by the tubing 5 which is screwed as at 6 into the tubing of larger diameter indicated at 7.

The nozzle 2 consists of a head casting or screw cap 8 having an hexagonal head indicated at 9, and a bore 10 which tapers down to a smaller opening indicated at 11 (Figures 2 and 3). There is a cap 12 which screws over a small diameter portion of the member 8, this cap serving to clamp a pair of washers 13, 14 to the right hand end of the member 9. The washer 13 is made of rubber and constitutes a gasket, and the washer 14 is composed of a hard non-corrosive metal having a very small opening 15 through which fluid issues as a spray.

The trigger shut-off 3 may be of any suitable material but as illustrated is formed essentially of a cylinder 16 from which extends a hollow handle element 17. The latter is also provided with a downwardly extending lug 24 which serves as a stop for the trigger handle 23. The lower surface of the handle 17 and the upper surface of the trigger handle 23 are preferably so shaped that when the composite handle is gripped the two

handle elements are readily accommodated within in the hand. Within the cylinder 16 there is provided suitable mechanism by which when the trigger handle 23 is moved against the handle element 17, a passageway is provided between the interior of the element 17 and the barrel 1. The liquid insecticide is introduced into the handle 17 in any suitable manner and placed under pressure so that the flow of the liquid is controlled by the movements of the trigger 23. Inasmuch as, the present invention is not directed especially to the handle mechanism, no further description of this device appears necessary or desirable.

Spray volume controlling mechanism at the nozzle end of gun

Within the head casting 8 and also extending within the pipe 7, there is a whirler mechanism comprising a cylindrical member 50 having a countersunk opening 51 at one end and terminating at the other end in a threaded extension 52. The cylinder 50 is provided with a plurality of angular slots 53 (Figure 6) which conveniently may be sawed into the wall of the cylinder.

The threaded end 52 of the member 50 is received in the right hand end of a vane-shaped member, the vanes of which there may be four, as indicated at 54 in Figure 5, extending throughout most of the length of the member. The distance across each pair of oppositely disposed vanes is only slightly less than the internal diameter of the barrel 7, so that the vanes serve to center the cylinder 50 with respect to the bore 10. The left hand end of this member terminates in a flat portion indicated at 55 (Figures 1 and 4), which is provided with a transversely extending slot 56. This slot receives a pin 57 extending upwardly from, and integrally secured to a plate 58 which forms a part of a cylindrical stem 59.

The plate 58 rests on the upper surface of a hollow cylindrical member 60, which is closed at the lower end except for an opening through which the cylindrical stem 59 extends. The cylinder 60 is provided with an outwardly extending flange 61 and a threaded portion 62 which is screwed into an internally threaded boss 63 extending downwardly from the pipe or barrel 7.

There is a compression spring 64 loosely surrounding the stem 59 and contained within the cylinder 60, this spring resting on the washer 64' and packing material 65. The lower end of the stem 59 is received in an opening formed at the upper surface of a handle grip 66, the set screw 67 serving to secure the handle 66 to the stem. The handle is hollow, and the lower end is left open in order to drain off small amounts of fluid which might leak past the under side of the plate 58 and the washer 64' and through the packing 65. It will be noted in this connection that the spring 64 bears downwardly against the packing 65 thus tending to maintain the packing in a tight condition and preventing any substantial amounts of fluid from passing through the handle 66.

Operation of the nozzle and its adjustments

Assume that the trigger 23 has been operated to admit a spray solution under pressure through the pipe 5 into the pipe 7, this solution will pass between the quadrantal vanes 54 and on striking the outside periphery of the cylinder 50 will pass through the angular slots 53 into the bore 10 and emerge from the gun at the small opening 15. The purpose of the vanes 54 is to straighten out

the stream, i. e. to eliminate any undesired whirl or eddy current motion within the tube 7.

The effect of passing the solution through the angular slots 53 is to cause the stream to be given a rapid whirl so that when the solution is ejected at the opening 15 with great force, the solution particles constitute a whirling mass, which as will be pointed out hereinafter, may be controlled all the way from a mist form to a coarse straight stream. The amount of the whirl is determined by the angularity and number of slots 53, also by the pressure of the fluid in the pipe 7. The degree with which the fluid is broken into fine particles, and the fineness of these particles, i. e. the state of the mist is determined by the distance that the cylinder 50 penetrates the bore 10.

As the cylinder 50 is moved to the left, greater quantities of the fluid are permitted to pass without obstruction into the bore 10 so that the stream emitted at the opening 15 is a straight spray with greater carrying power than a stream in mist form. The cylinder 50 is adjusted longitudinally by rotating the handle 66, which causes the pin 57 to rotate about the axis of the stem 59 and to carry with it the flattened portion 55 of the vane-shaped member.

Thus, when the handle 66 is rotated from its position shown in Figure 2, the pin 57 in effect moves to the left until it reaches its maximum left hand position, shown in Figure 3 corresponds to a half revolution turn of the handle 66.

In the normal operation of the spray gun the user will grip the handle 66 with his left hand and the combined trigger 23 and handle 17 with his right hand, directing the barrel at the position which it is desired to cover with the spray solution, and the handle in the left hand can be turned giving the exact type of spray that is desired.

It will be understood that the mist form of spray is desirable when the gun is placed close to the plant or tree being sprayed and wide coverage is desired, whereas the coarse or straight form of stream is desired when long throw is necessary, as when spraying the tops of trees. Consequently, by simply turning the hand grip 66 through an angle of less than 180° complete control of the character of the spray is obtained all the way from a fine mist form to a straight or long distance carrying stream.

In order to reduce the weight of the spray gun as much as possible, and to eliminate corrosion, it is desirable to make most of the parts of aluminum, by casting. Those parts which are subjected to the greatest wear, for example, the spray adjusting mechanism 57, 58, 59 and 60 are made of a hard metal, such as brass or bronze.

It will be further evident that there are absolutely no welded joints within the gun and such few joints as are necessary are all of the screw type permitting a ready dis-assembly of the various parts for replacement and cleaning.

The combination of the pistol grip handle 17 and the position of the adjusting handle 66 affords a natural and easy position for the operator to hold the gun, at the same time giving the operator a firm grip on the gun against the recoil resulting from the discharge of the liquid at high pressures.

While I have explained the improved spray gun from the standpoint of spraying plants, etc., it will be understood that the gun may be used for spraying other liquids on other surfaces, such as spraying cold water, paint, or distributing of etching acids over metal surfaces.

It will be understood that I desire to comprehend within my invention such modifications as may come within the claims and scope of my invention.

Having thus fully described my invention, what I claim as new and desire to secure by Letters Patent, is:

1. A spray gun comprising a barrel, said barrel including a first and a second length of tubing, said tubing lengths being straight from end to end, means on adjacent ends of said tubing lengths for attaching them together in axial alignment whereby to form a straight passageway interiorly from end to end of said lengths of tubing and thereby prevent turbulence of fluids passing therethrough, said first length of tubing having a nozzle and having a threaded boss located on its under side intermediate its ends, a hollow substantially cylindrical member threadedly engaging said boss and extending below said first tubing length, a rotatable handle grip extending downwardly from said hollow member and forming a continuation thereof, a stem attached to said handle grip and extending upwardly through said member and having an upper end including an offset pin which projects into said first tubing length, a rigid rod member extending lengthwise of said first length of tubing and having an aperture at one end engaging said pin and a valve member at its opposite end, said nozzle having a restricted passageway adapted to be at least partially closed, or fully closed by rotation of said handle grip, said second length of tubing having a hollow rigid handle element and a pivoted trigger handle extending downwardly therefrom and being in the same plane as said rotatable hand grip on said first tubing, and a valve on said second tubing length and operatively connected to said pivoted trigger handle to control the passage of fluid from within said handle element to said tubing lengths.

2. A spray gun comprising a barrel, said barrel including a first and a second length of tubing, said tubing lengths being straight from end to end, means on adjacent ends of said tubing lengths for attaching them together in axial alignment whereby to form a straight passageway interiorly from end to end of said lengths of tubing and thereby prevent turbulence of fluids passing therethrough, said first length of tubing having a nozzle and having a threaded boss located on its under side intermediate its ends but positioned adjacent to said means for attaching said tube lengths together, a hollow substantially cylindrical member threadedly engaging said boss and extending below said first tubing length, a rotatable handle grip of substantially cylindrical shape extending downwardly from said hollow member and forming a continuation thereof, a stem attached to said handle grip and extending upwardly through said member and having an upper end including an offset pin which projects into said first tubing length, a rigid rod member extending lengthwise of said first length of tubing and having an aperture at one end engaging said pin and a valve member at its opposite end,

said nozzle having a restricted passageway adapted to be at least partially closed, or fully closed by rotation of said handle grip, said second length of tubing having a hollow rigid handle element and a pivoted trigger handle extending downwardly therefrom and being in the same plane as said rotatable hand grip on said first tubing, and a valve on said second tubing length and operatively connected to said pivoted trigger handle to control the passage of fluid from within said handle element to said tubing lengths.

3. A spray gun comprising a barrel, said barrel including a first and a second length of tubing, said tubing lengths being straight from end to end, means on adjacent ends of said tubing lengths for attaching them together in axial alignment whereby to form a straight passageway interiorly from end to end of said lengths of tubing and thereby prevent turbulence of fluids passing therethrough, said first length of tubing having a nozzle and having a threaded boss located on its under side intermediate its ends, a hollow substantially cylindrical member threadedly engaging said boss and extending below said first tubing length, a rotatable handle grip extending downwardly from said hollow member and forming a continuation thereof, a stem attached to said handle grip and extending upwardly through said member and having an upper end including an offset pin which projects into said first tubing length, a rigid rod member extending lengthwise of said first length of tubing and having an aperture at one end engaging said pin and a valve member at its opposite end, said nozzle having a restricted passageway adapted to be at least partially closed, or fully closed by rotation of said handle grip, said second length of tubing having a hollow rigid handle element and a valve operator mounted adjacent said rigid handle element, said rigid handle element and said rotatable hand grip being in substantially the same plane, and a valve on said second tubing length and operatively connected to said trigger handle to control the passage of fluid from within said handle element to said tubing lengths.
